APPROVED

UNITED STATES PATENT OFFICE.

THOMAS H. SPENCE, OF SAN FRANCISCO, CALIFORNIA.

SHIRT-COLLAR.

1,186,700.

Specification of Letters Patent. Patented June 13, 1916.

Application filed November 10, 1915. Serial No. 63,667.

To all whom it may concern:

Be it known that I, THOMAS H. SPENCE, a citizen of Panama, residing in the city and county of San Francisco and State of California, have invented new and useful Improvements in Shirt-Collars, of which the following is a specification.

My invention relates to improvements in detachable collars for shirts, and is especially applicable to soft folded collars used without stiffening.

The invention consists in providing means to retain such collars in a smooth, upright and properly closed condition when in place.

It also comprises details of construction which will be more fully explained by reference to the accompanying drawings, in which—

Figure 1 is a view showing the two parts of the collar opened out flat. Fig. 2 shows the collar in its folded form.

Soft, folding collars are worn for comfort, especially in warm weather, but are often unsightly by reason of the difficulty of keeping the front edges closed and symmetrical.

It is the object of my invention to overcome the difficulty and improve the fit of the collar.

As shown, A and B are the inner and outer folds of the collar, foldable on the line 2. The inner member A which lies contiguous to the shirt band is secured thereto by means of a button hole 3, engaging a button 35 at the rear and two button holes 4 and 5 so placed near the ends, as to overlap and engage with the front collar button at 6. In order to fit this inner member more smoothly, a button 7 is fixed to this member above and back of the button hole 4, and a corresponding button hole 8 is made at the opposite upper corner of this inner member. These hold the top of this portion in place. The outer portion B has button holes 9 and 45 10 made near the upper and lower corners. These button holes are adapted to receive the link connected buttons 12; the links being of such a length that they pass beneath the front ends of the folded over outer por-

tions, so that the latter will be thus held 50 spaced and prevented from crushing down or spreading away from each other.

If a cravat is used the ends may pass between the upper and lower buttons and be tied in any desired manner, or the finish of 55 the collar may be complete without a tie if desired. In order to maintain the tie or cravat in place between the folds of the collar, I fix light tapes 13 transversely across the ends of the outer portion, so that the 60 collar and tie may be removed without separation. The link buttons act to hold the necktie knot from up or down movement and the tapes serve to assist in holding the tie ends between the buttonholes 9 and 10, in 65 applying the tie to the collar and while applying the link buttons.

Having thus described my invention, what I claim and desire to secure by Letters Patent is—

In a soft folding collar, an outer and an inner member connected together, the outer member having its ends formed with a pair of upper and a pair of lower button-holes adapted to receive connecting means, said 75 upper and lower button-holes being vertically spaced a distance to admit the passage therebetween of the ends of a necktie, the upper pair of button-holes being located close to the top edge of the collar so that 80 the upper connecting means will engage the necktie knot and hold same from upward movement and the ends of the outer member being spaced to permit the necktie ends to pass same, the connecting means for the 85 lower pair of button-holes being adapted to engage the necktie knot to hold same against downward movement and tapes affixed to the outer member in a position adjacent to the inner ends of the respective buttonholes. 90

In testimony whereof I have hereunto set my hand in the presence of two subscribing witnesses.

THOMAS H. SPENCE.
